UNITED STATES PATENT OFFICE.

SIMON WROBEL, OF NEW YORK, N. Y., ASSIGNOR TO S. WROBEL SLIPPER CO., INC.,
OF NEW YORK, N. Y., A CORPORATION OF NEW YORK.

DESIGN FOR A BOUDOIR SLIPPER.

Application filed June 14, 1928. Serial No. 27,129. Term of patent 3½ years.

To all whom it may concern:

Be it known that I, SIMON WROBEL, a citizen of the United States, residing at New York, county and State of New York, have invented a new, original, and ornamental Design for a Boudoir Slipper, of which the following is a specification, reference being had to the accompanying drawing, forming part hereof.

The figure is a perspective view of a boudoir slipper showing my new design.

I claim:

The ornamental design for a boudoir slipper, as shown.

SIMON WROBEL.
